UNITED STATES PATENT OFFICE.

LOUIS W. CARROLL, OF RIVERSIDE, ILLINOIS, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,324,796.

Specification of Letters Patent. Patented Dec. 16, 1919.

Application filed September 14, 1917. Serial No. 191,354.

To all whom it may concern:

Be it known that I, LOUIS W. CARROLL, a citizen of the United States, residing at Riverside, in the county of Cook and State 5 of Illinois, have invented certain new and useful Improvements in Telephone-Exchange Systems, of which the following is a full, clear, concise, and exact description.

This invention relates to telephone exchange systems, and more particularly to 10 such systems of the central office type.

The object of this invention is to provide a system of this character in which an operator's telephone set is automatically connected to and disconnected from a calling telephone line, and a source of ringing current is automatically connected to and disconnected from a called line with a minimum amount of apparatus.

20 In accordance with this invention, there is provided a link circuit equipped with four relays, two of which are supervisory relays and the other two, one a ringing relay and the second a tripping relay. One 25 of the supervisory relays and the ringing relay coöperate to control the connection of the operator's telephone set to the link circuit. The supervisory relay associated with the answering end of the link circuit also 30 coöperates with the tripping and ringing relays to disconnect ringing current from the called line when a call is abandoned by the calling party.

For a more complete understanding of this 35 invention, reference should be had to the following description considered in connection with the accompanying drawing containing one embodiment of this invention.

In the drawing there are shown two telephone lines, A and B, which terminate at 40 a central office, at which is located a cord circuit C for interconnecting these lines. All apparatus is shown in its normal and unactuated condition. It is thought that 45 this invention can best be understood from a description of the operation of the system shown in the drawing, and it will be so described.

Subscriber A, in initiating a call, removes 50 the receiver from the switchhook and causes the energization of line relay 5, whereupon the line lamp 6 is lighted to furnish a signal to the central office operator. The operator, observing the lighted condition of line lamp 55 6, inserts answering plug 7 into line jack 8,

whereupon cut-off relay 10 is operated over a circuit from battery through the lower normal contact of answering supervisory relay 9, answering supervisory lamp 11, sleeve contacts of the answering plug 7 and line jack 8, and the winding of cut-off relay 10 to ground. Cut-off relay 10 in operating disconnects the line relay 5 from the line, whereupon the line relay releases, extinguishing the line lamp 6. Supervisory lamp 65 11 would light were it not for the fact that the answering supervisory relay 9 is also actuated upon the connection of the answering plug with the line jack, thereby connecting resistance 12 in circuit with the lamp 70 11 and preventing the lamp from presenting a signal. Answering supervisory relay 9 is energized over a circuit from battery through the lower winding of this relay, ring contacts of the answering plug 7 and line jack 8, over one side of the line, through the substation apparatus, back over the other side of the line, tip contacts of line jack 8 and answering plug 7, and the upper winding of relay 9 to ground. Answering supervisory relay 9 in addition to preventing 75 the lighting of supervisory lamp 11, connects the operator's telephone set to the talking strands of the cord circuit and thence to the calling line A.

The operator upon being advised that the calling subscriber A desires to be connected with the line of subscriber B, inserts calling plug 17 into line jack 18, thereby causing the energization of ringing relay 19 80 and cut-off relay 20 over a circuit from battery through the lower alternate contact of answering supervisory relay 9, normal contact of tripping relay 21, winding of ringing relay 19, sleeve contacts of the calling plug 17 and line jack 18, and the winding of cut-off relay 20 to ground. The energization of cut-off relay 20 disconnects line relay 22 from line B. Calling supervisory lamp 23 is also lighted over a circuit from battery through the normal contact of calling supervisory relay 24, lamp 23, sleeve contacts of the calling plug 17 and line jack 18, and the winding of cut-off relay 20 to ground. Ringing relay 19 is of the so 85 called two-step type which, when fully energized, operates all of its contacts and when partially energized, actuates only a portion of its contacts. This ringing relay 19 is designed and adjusted so that 90 100 105 110

when it is fully energized over the hereinbefore traced circuit, it opens all of its normal contacts and closes its alternate contacts. The opening of its normal contacts 30 and 31 disconnects the operator's telephone set from the talking strands of the cord circuit. The opening of its normal contacts 32 and 33 introduces breaks in the talking strands of the cord circuit, and the closure of its alternate contacts connects a source of ringing current 35 to line B. This circuit for ringing current may be traced from the source of ringing current 35 through the lower winding of tripping relay 21, lower alternate contact of ringing relay 19, ring contacts of the calling plug 17 and line jack 18, over one side of the line B, through call bell 36 and condenser 37, back over the other side of line B, tip contacts of the line jack 18 and calling plug 17, and the upper alternate contact of ringing relay 19 to ground. Current traversing this path causes the operation of call bell 36. The called party in response to the operation of call bell 36, removes the receiver from the switchhook, thereby establishing a lower resistance path for the ringing current from source 35, whereupon tripping relay 21 is energized. Upon the energization of this tripping relay 21, its contact is opened, thereby removing the short circuit of the upper winding of tripping relay 21 which is thereupon included in circuit with the winding of ringing relay 19. The inclusion of the upper winding of tripping relay 21 in circuit with the ringing relay 19 causes a reduced flow of current through ringing relay 19, consequently a partial deenergization thereof, whereupon tripping relay 19 actuates over a portion of its contacts. The contacts actuated are the upper and lower alternate contacts which are opened, and the normal contacts 32 and 33 which are closed; the opening of the alternate contacts disconnecting the source of ringing current from the called line, and the closure of the normal contacts 32 and 33 closing the breaks in the talking strands of the cord circuit. The closure of contacts 32 and 33 connects the calling supervisory relay 24 in circuit with the called line, which thereupon operates to include resistance 40 in circuit with the calling supervisory lamp 23, which is thereby extinguished. Ringing relay 19, when only partially energized, as when the upper winding of tripping relay 21 is in circuit therewith maintains its normal contacts 30 and 31 open, thereby maintaining the operator's telephone set disconnected from the cord circuit.

Upon the conclusion of the conversation, subscribers A and B restore the receivers to the switchhooks, causing the release of both supervisory relays which thereupon

short-circuit the resistances 12 and 40, permitting both supervisory lamps 11 and 23 to be lighted to furnish disconnection signals. The operator may thereupon withdraw the plugs from the jacks, whereupon all apparatus is restored to normal position.

If, while the answering plug of the cord circuit is connected with line A, the receiver of which is off the switchhook, and the calling plug is connected with line B, the receiver of which has not been removed from the switchhook, and the calling subscriber A abandons the call, ringing current is thereby automatically disconnected from the called line B. This is brought about in the following manner.

Subscriber A in restoring the receiver to the switchhook causes the deenergization of answering supervisory relay 9, which thereupon opens its lower alternate contact which is in the short circuit of the upper winding of the tripping relay 21. This upper winding of tripping relay 21 is thereupon included in circuit with the ringing relay 19 to cause the partial deenergization of this ringing relay in the manner hereinbefore described. Ringing current is thereby disconnected from the called line in the manner hereinbefore described. Upon the release of the answering supervisory relay 9, answering supervisory lamp 11 is lighted to furnish a disconnect signal. Calling supervisory lamp 23 is also lighted at this time, so that the operator upon observing the lighted condition of both lamps may withdraw the plugs from the jacks.

What is claimed is:

1. A telephone exchange system comprising telephone lines, a link circuit for interconnecting the lines, a source of ringing current, a ringing relay energized to one degree due to the connection of the link circuit with one of the lines to connect therewith the source of ringing current, and means effective upon the response of the called line for causing the energization of the ringing relay to another degree thereby to disconnect the source of ringing current from the called line.

2. A telephone exchange system comprising telephone lines, a link circuit for interconnecting the lines, a source of ringing current, a ringing relay energized to one degree upon the connection of the link circuit with one of the lines to connect therewith the source of ringing current, and a relay actuated upon the response of the called line for causing the energization of the ringing relay to another degree thereby to disconnect the source of ringing current from the called line.

3. A telephone exchange system comprising telephone lines, a link circuit for interconnecting the lines, a source of ringing current, a ringing relay energized to one de-

gree upon the connection of the link circuit with one of the lines to connect therewith the source of ringing current, a tripping relay in circuit with the source of ringing current energized upon the response of the called line, and a resistance connected in circuit with the ringing relay upon the energization of the tripping relay thereby to cause the partial deenergization of the ringing relay whereby the source of ringing current is disconnected from the called line.

4. A telephone exchange system comprising telephone lines, a link circuit for interconnecting the lines, a source of ringing current, a ringing relay fully energized upon the connection of the link circuit with one of the lines to connect therewith the source of ringing current, a tripping relay having a winding in circuit with the source of ringing current for energizing the tripping relay upon the response of the called line, and a second winding for the tripping relay included in circuit with the ringing relay upon the energization of the tripping relay thereby causing the partial deenergization of the ringing relay, whereby the source of ringing current is disconnected from the called line.

5. A telephone exchange system comprising telephone lines, a link circuit for interconnecting the line, an operator's telephone set, a relay in the answering end of the link circuit energized upon the connection of the answering end of the link circuit with a calling line to connect therewith the operator's telephone set, a source of ringing current, a ringing relay energized to one degree upon the connection of the link circuit with another line to connect therewith a source of ringing current, and means effective upon the response of the called line to cause the energization of the ringing relay to another degree thereby to disconnect the ringing current from the called line.

45 6. A telephone exchange system comprising telephone lines, a link circuit for interconnecting the lines, an operator's telephone set, a supervisory relay in the link circuit energized upon connection of the link circuit with the calling line to connect therewith the operator's telephone set, a source of ringing current, a ringing relay energized to one degree due to the connection of the link circuit with another line to connect therewith the source of ringing current, and means effective upon the response of the called line to cause the energization of the ringing relay to another degree thereby to disconnect the source of ringing current from the called line.

7. A telephone exchange system comprising telephone lines, a link circuit for interconnecting the lines, an operator's telephone set, a supervisory relay in the link circuit energized upon connection of the link cir-

cuit with the calling line to connect therewith the operator's telephone set, a source of ringing current, a ringing relay energized to one degree upon connection of the link circuit with another line to connect therewith the source of ringing current, and a relay energized upon the response of the called line thereby to cause the energization of the ringing relay to another degree, whereby the source of ringing current is disconnected from the called line.

8. A telephone exchange system, comprising telephone lines, a link circuit for interconnecting the lines, an operator's telephone set, a relay in the link circuit energized upon connection thereof with a calling line to connect therewith the operator's telephone set, a source of ringing current, a ringing relay energized to one degree upon connection of the link circuit with another line to connect therewith the source of ringing current, a tripping relay in circuit with the source of ringing current and actuated upon the response of the called line, and a resistance connected in circuit with the ringing relay upon the actuation of the tripping relay thereby to cause the energization of the ringing relay to another degree, whereby the source of ringing current is disconnected from the called line.

9. A telephone exchange system comprising telephone lines, a link circuit for interconnecting the lines, an operator's telephone set, a relay responsive to the connection of the link circuit with a calling line to connect therewith the operator's telephone set, a source of ringing current, a ringing relay fully energized upon connection of the link circuit with another line to connect therewith the source of ringing current, a tripping relay having a winding in circuit with the source of ringing current for energizing the tripping relay upon the response of the called line, and another winding for the tripping relay brought into circuit with the ringing relay upon the energization of the tripping relay thereby to cause the partial deenergization of the ringing relay, whereby the source of ringing current is disconnected from the called line.

10. A telephone exchange system comprising telephone lines, a link circuit connected with one of the lines as a calling line, a source of ringing current, a ringing relay energized to one degree upon the connection of the link circuit with another line to connect therewith the source of ringing current, a relay in the link circuit controlled from the calling line, and means effective upon the deenergization of said last mentioned relay for causing the energization of the ringing relay to another degree thereby to disconnect the source of ringing current from the called line.

11. A telephone exchange system compris-

115

120

125

ing telephone lines, a link circuit connected with one of the lines as a calling line, a relay in the link circuit controlled from the calling line, a source of ringing current, a ringing 5 relay energized to one degree upon connection of the link circuit with another line to connect therewith the source of ringing current, and the relay effective upon the de-energization of the relay controlled from 10 the calling line for causing the energization of the ringing relay to another degree thereby to disconnect the source of ringing current from the called line.

12. A telephone exchange system comprising 15 telephone lines, a link circuit connected with one of the lines as a calling line, a supervisory relay in the link circuit controlled from the calling line, a source of ringing current, a ringing relay fully energized 20 upon connection of the link circuit with another line to connect therewith a source of ringing current, and a resistance included in circuit with the ringing relay upon the de-energization of the supervisory 25 relay for causing the partial de-energization of the ringing relay thereby to disconnect the source of ringing current from the called line.

13. A telephone exchange system comprising 30 telephone lines, a link circuit connected with one of the lines as a calling line, a supervisory relay in the link circuit controlled from the calling line, a source of ringing current, a ringing relay fully energized upon 35 connection of the link circuit with another line to connect therewith the source of ringing current, and a third relay normally short-circuited while the supervisory relay is energized over a calling line and brought 40 into circuit with the ringing relay upon the de-energization of the supervisory relay to cause the partial de-energization of the ringing relay thereby to disconnect the source of ringing current from the called line.

45 14. A telephone exchange system comprising telephone lines, a link circuit connected with one of the lines as a calling line, a supervisory relay in the link circuit controlled from the calling line, a source of ringing

current, a ringing relay energized to one degree upon connection of the link circuit with another line to connect therewith the source of ringing current, and means effective upon either the de-energization of the supervisory relay or upon the response of 55 the called line for causing the energization of the ringing relay to another degree thereby to disconnect the source of ringing current from the called line.

15. A telephone exchange system comprising 60 telephone lines, a link circuit connected with one of the lines as a calling line, a supervisory relay in the link circuit controlled from the calling line, a source of ringing current, a ringing relay energized to one degree 65 upon connection of the link circuit with another line to connect therewith the source of ringing current, and a relay effective upon either the de-energization of the supervisory relay or upon the response of 70 the called line for causing the energization of the ringing relay to another degree thereby to disconnect the source of ringing current from the called line.

16. A telephone exchange system comprising 75 telephone lines, a link circuit connected with one of the lines as a calling line, a supervisory relay in the link circuit controlled from the calling line, a source of ringing current, a ringing relay energized to one degree 80 upon connection of the link circuit with another line to connect therewith the source of ringing current, and a tripping relay in circuit with the source of ringing current and energized upon the response of the 85 called line, and a resistance coil included in circuit with the ringing relay upon either the de-energization of the supervisory relay or the energization of the tripping relay 90 for causing the energization of the ringing relay to another degree thereby to disconnect the source of ringing current from the called line.

In witness whereof, I hereunto subscribe my name this 27th day of August, A. D. 95 1917.

LOUIS W. CARROLL.
